COMBINED TOOTHPASTE DISPENSER, GLASS HOLDER AND BATHROOM CABINET

Joseph La Reis, 3727 E. 5th St., Tucson, Ariz.

Filed Oct. 26, 1961, Ser. No. 67,272

Term of patent 14 years

(Cl. D4—3)

FIGURE 1 is a perspective view illustrating the top and one side of a combined toothpaste dispenser, glass holder and bathroom cabinet embodying my new design,

The dominant features of my design reside in the portions shown in full lines.

I claim:

The ornamental design for a combined toothpaste dispenser, glass holder and bathroom cabinet, as shown and described.
